UNITED STATES PATENT OFFICE.

WILLIAM J. EMMITT, OF COLUMBUS, OHIO.

STEAM OR FLUID-PRESSURE ENGINE.

SPECIFICATION forming part of Letters Patent No. 697,136, dated April 8, 1902.

Application filed August 19, 1901. Serial No. 72,557. (No model.)

To all whom it may concern:

Be it known that I, WILLIAM J. EMMITT, a citizen of the United States, residing at Columbus, in the county of Franklin and State 5 of Ohio, have invented certain new and useful Improvements in Steam or Fluid-Pressure Engines; and I do hereby declare the following to be a full, clear, and exact description of the invention, such as will enable others skilled in the art to which it appertains to make and use the same.

The object of this invention is to provide an improved fluid-pressure engine, or, more broadly, a fluid-pressure engine especially 15 adapted for propelling automobiles and other vehicles, which shall be of simple and economical construction and which can be started, stopped, reversed, or varied in its speed by the operation of a single handle.

20 The features of novelty are pointed out in the claim appended hereto.

In the accompanying drawings, in which I have illustrated one embodiment of the invention, Figure 1 is a sectional view on the 25 line $x-x$, Fig. 2, of the shaft upon which the cylinders are hung and oscillate and also the controlling-valve and the steam chest or chamber. Fig. 2 is a transverse sectional view taken on the line $y-y$, Fig. 1. Fig. 3 is a view 30 of the face of the controlling-valve. Fig. 4 is a sectional view of a cylinder and the shaft upon which it is hung. Fig. 5 is a view in side elevation of the entire engine.

The supporting-frame includes two side 35 pieces 1. In the upper portion of the frame is supported the stationary shaft 2, having two longitudinal passages 2^a and 2^b with lateral ports 2^c and 2^d, there being such ports for each of the three cylinders 8, 8^a, and 8^b. 40 Threaded to the outer end of the shaft 2 and constituting practically a part of the shaft is shown to be a section 3, containing passages forming continuations of the passages 2^a and 2^b as well as a portion of the exhaust-passage 45 or port 3^b. Coupled to this piece 3 by a coupling 4^b is the steam-chest 4, containing the inlet-port 4^a for the admission of the live steam, and ports or passages constituting further 50 continuations of the passages 2^a and 2^b in the shaft 2 and the exhaust passage or port 3^b in the part 3. A pin 3^a to engage a properly located hole in the part containing the cham-

ber 4 will assist in locating correctly the two parts with respect to each other. In this chamber 4 is placed the rotative controlling 55 valve 5, having a through-port 5^a and an arc-shaped recess-port 5^b. The ports of the part 4 that form continuations of the passages 2^a and 2^b and the exhaust passage or port 3^b are equidistantly located, corresponding to the 60 disposition of such passages, as is shown in Fig. 2, and the two ports in the controlling-valve 5 are so located that when the through-port 5^a aligns with one of the passages 2^a and 2^b the recessed port establishes communication 65 of the other with the exhaust-passage 3^b. The valve 5 is engaged by a rotatable stem 6, extending through a suitably-boxed opening in a hood 7 on the outer end of the steam-chamber, the outer end of said stem being 70 furnished with a convenient handle 6^b, by which the valve can be manipulated. This handle can also be provided with a spring-actuated pin 6^b to enter any of several holes 75 in the outer side of the hood 7 to indicate the proper position of the valve 5 and hold it in such position to admit, regulate the admission to, or shut off steam from the passages 2^a or 2^b. I have not shown in my drawings the spring that actuates the pin, because it 80 constitutes no part of my present invention and is a well-understood construction, and, moreover, the construction can be dispensed with entirely and other means for performing its function substituted. 85

In Fig. 3 I have indicated the cylinders 8, 8^a, and 8^b of three single-acting engines as hung to oscillate upon the shaft 2. The head of each of these cylinders has a port 11, which as the cylinder oscillates is brought to coincide successively with the ports 2^a and 2^b. The piston-rods 9, 9^a, and 9^b of these cylinders are connected by ordinary straps to the cranks of a power-shaft 10, journaled in the lower part of the frame, said cranks extending radially from the axis of said shaft one hundred and twenty degrees apart, so that while one cylinder is taking a head of steam another has a full head and the third is exhausting. Dead-centering is thus impossible. 90 By turning the valve 5 to shift the through-port 5^a from, say, passage 2^a to passage 2^b the direction of motion of the engine is reversed, and by turning said valve so that the 95 100

port 5^a is throttled between the passages 2^a and 2^b the engine is stopped altogether. The speed of the engine in either direction can be varied by turning the valve 5 to vary the size of the opening made between the port 5^a into the passage 2^a or 2^b . Thus it will be observed that with the single handle 6^a the engine can be started in either direction, stopped, reversed, and have its speed regulated, and all this without the employment of links or complex auxiliary devices.

An adjustable bushing 12 at one end of the shaft 2 can be used to draw the cylinders sufficiently close together as to prevent side play on the shaft.

It is an obvious expedient to inclose the lower end of the casing to form a receptacle for oil in which the crank-shaft 10 can work.

The shaft 2, the part 3, and the end of the steam-chest 4 adjacent the part 3 can be viewed as one structure containing the steam-passages.

While I have referred to my engine herein described as a "steam-engine," steam is not

necessarily the operating agent, because any fluid under pressure can be employed.

What I claim, and desire to secure by Letters Patent, is—

In a fluid-pressure engine, a stationary shaft containing longitudinal passages 2^a and 2^b and an exhaust-port 3^b opening on one end of said shaft, cylinders hung to oscillate on said shaft, ports from the passages 2^a and 2^b for each of said cylinders, a shiftable valve 5 containing a single through-port 5^a and a connected double-recess port 5^b , said shiftable valve working on the end of said shaft and adapted to admit live pressure through the port 5^a to either of the passages 2^a and 2^b and exhaust from the other through the valve-port 5^b and shaft-port 3^b , substantially as described.

In testimony whereof I affix my signature in presence of two witnesses.

WILLIAM J. EMMITT.
